[57] CLAIM

The ornamental design of a combined cigarette case and ashtray, as shown and described.

DESCRIPTION

FIG. 1 is an enlarged, right front perspective view of a combined cigarette case and ashtray showing my new design with the lid closed;

FIG. 2 is a front elevational view thereof;

FIG. 3 is a bottom plan view thereof;

FIG. 4 is a top plan view thereof;

FIG. 5 is a rear elevational view thereof;

FIG. 6 is a left end elevational view thereof;

FIG. 7 is a right end elevational view thereof; and

FIG. 8 is an enlarged, right front perspective view of a cigarette case and ashtray showing my new design with the lid in the open position for the purpose of a complete disclosure.
